KITE STRING ELEVATING SPINNER

Emil M. Bahnik, Los Angeles, Calif.

Application June 18, 1956, Serial No. 41,944

Term of patent 14 years

(Cl. D34—15)

Fig. 1 is a side elevational view of a kite string elevating spinner, showing my new design;

Fig. 2 is a bottom plan view thereof;

Fig. 3 is a top plan view thereof;

Fig. 4 is a side elevational view thereof to an enlarged scale; and

Fig. 5 is an opposite side elevational view thereof.

The broken line showing of a kite in Fig. 1 is for illustrative purposes only.

I claim:

The ornamental design for a kite string elevating spinner, substantially as shown and described.
